(21) Appl. No.: **29/115,891**

CLAIM

(22) Filed: **Dec. 23, 1999**

The ornamental design for a female connector for medical haemodialysis lines, as shown and described.

(30) **Foreign Application Priority Data**

DESCRIPTION

Jul. 20, 1999 (IT) TO9900200

FIG. 1 is a perspective view of a female connector for medical haemodialysis lines and shows our design;

(51) LOC (7) Cl. **24-02**

FIG. 2 is a plan view of the female connector for medical haemodialysis lines;

(52) U.S. Cl. **D24/129**

FIG. 3 is a right side view of the female connector for medical haemodialysis lines;

(58) Field of Search D24/129; D23/259,
D23/262; 604/93.01, 533, 905; 285/38,
332, 393, 423, 921

FIG. 4 is a left side view of the female connector for medical haemodialysis lines;

(56) **References Cited**

FIG. 5 is a front view from above of female connector for medical haemodialysis lines; and,

U.S. PATENT DOCUMENTS

FIG. 6 is a rear view of the female connector for medical haemodialysis lines.
